METHOD FOR WRAPPING CONFECTIONS

Constantine Contos and Soter G. Contos,
Chicago, Ill.Application June 26, 1931, Serial No. 547,148
Renewed January 12, 1934

4 Claims. (Cl. 93—2)

This invention relates to certain novel improvements in method for wrapping confections, and has for its principal object the provision of an improved method of this character which will be highly efficient in use.

It is an object of this invention to provide a method by which a number of individual pieces of candy or other like confections may be wrapped into a package in a more sanitary manner than has been possible heretofore in the art, with greater economy in time and labor, and with a minimum of manual operations.

It is another object of the invention to provide a method for wrapping individual pieces of candy or other confection in a protective covering, such as cellophane, in such a manner that the resulting package will possess sufficient rigidity to withstand handling and so that the pieces of candy will be separated from each other in the resulting package.

Other objects will appear hereinafter.

The invention consists in the novel method to be hereinafter described and claimed.

The invention will be best understood by reference to the accompanying drawing showing the preferred form of construction, and in which:

Fig. 1 is a perspective view of a machine embodied in the invention;

Fig. 2 is a perspective view of a form or cap embodied in the invention and for placing a cellophane wrapper or the like about three sides of the group of pieces of candy;

Fig. 3 is a sectional view on line 3—3 in Fig. 2;

Fig. 4 is a sectional view on line 4—4 in Fig. 1;

Fig. 5 is a sectional view on line 5—5 in Fig. 1;

Fig. 6 is a view partly in side elevation and partly in section, illustrating the wrapping method at one stage in the execution thereof; and

Figs. 7, 8, 9 and 10 are views illustrating various steps in the execution of the method of wrapping.

Individual pieces of candy, such as sell for a cent each, are frequently wrapped in packages of, for example, five. The present method of wrapping these candies into packages of five or more is carried out by hand and is not only slow and costly from the standpoint of labor, but is objectionable from the sanitary point of view because of the necessity of frequently handling the individual pieces of candy. It is, therefore, an object of this invention to provide a method by which the number of manual operations in wrapping individual pieces of candy into a package containing a number of said pieces, will be

reduced to a minimum; and to provide means for carrying out the method.

A practical apparatus for carrying out the method is illustrated in the accompanying drawing and indicated generally at 10. This apparatus 60 10 includes a casing 11 that is provided with an apertured flange 12 by means of which the machine may be screwed to a work table so as to be conveniently operated by the worker. The top wall 16 of the casing 11 provides a work-supporting member or surface. In one side wall 65 of the casing 11 is a slot 13 through which projects an arm 14 that is pivotally mounted at its inner end, on ears 15 that project from the wall 70 of the casing.

Depending from the work-supporting top wall 16 of the casing 11 is a bracket 17 which is provided with apertures through which the lower ends of plungers 18 and 19 project. On each of these plungers 18 and 19 is a coil spring 20. The 75 upper ends of the plungers 18 and 19 are peened over a bar 21 which is adapted to be moved up and down between the arms 22 of the U-shaped bracket 17 by means of the arm 14 which projects through a U-shaped guide 23 that is fastened to, and depends from, the bar 21.

Slots 24 are arranged at intervals in the top wall 16 of the casing 10 and carried by the bar. 80 21 are spacer arms 25 which, as is evident, may be moved up and down through the slots 24 by manipulation of lever 14. Stops 26 are provided on the bottom of the guideway 23 to limit downward movement of the bar 21 and the spacer arms 25 so that when the lever 14 is depressed the spacers 25 will travel down until the top edges 90 27 thereof are disposed flush with the top wall 16.

The above described, or any other suitable apparatus, may be employed to carry out our improved candy wrapping method, as follows: At the beginning of the execution of the method, 95 the spacers 25 will be disposed as in Fig. 1. A spacer strip 28, of material such, for example, as waxed paper, is then laid across the tops of the spacer 25, as in Fig. 6, whereupon pieces 29 of candy or other confection, will be laid above 100 the strip 28 and pressed down between the spacers 25 so that the strip 28 will extend across three sides of each confection 29 (Fig. 6).

A sheet 30 of wrapping material, such, for example, as cellophane, is then placed over the tops 105 of the confections 29, Fig. 6. A cap 31, which is U-shaped in cross section and has an open face 32 is then laid over the confections 29, spacers 25, and strip 28, whereupon the lever arm 14 is depressed to lower the spacers 25 until the 110

tops of the spacers are flush with the top wall 16 of the casing. It is apparent that the confections 29, spaced by the strip 28, will now be disposed in the cap 31, as shown in Fig. 7. The cap 31 and the confections 29 and strip 28 are, therefore, inverted into the position of Fig. 9, and a stiffener strip 33 of stiff material such, for example, as cardboard or other fibrous material, is then laid over the spacer strip 28. The flaps 30' of the wrapper 30 are then folded together so as to enclose the confections 29, the stiffener strip 33 and spacer strip 28, so as to form a moisture-proof, sanitary wrapper, whereupon the cap or form 31 will be turned over so that the open side 32 is down, and the complete package dropped therefrom, ready to be packed for shipping.

The stiffener strip 33 gives rigidity to the complete package 34 and keeps the pieces or confections 29 in alignment. It is intended that, in use, the lever 14 be attached by suitable means (not shown) to a foot treadle located under the work table on which the casing 11 will be disposed so that the worker may operate spacers 25 by foot while having both hands free for performing the several steps in the method.

From the foregoing description of the invention, it will be seen, therefore, that the present invention provides a method for wrapping individual confections into a package in a rapid, labor-saving and sanitary manner, with a minimum of manual operations; and that the invention provides a practical apparatus for carrying out the method.

While we have illustrated and described the preferred method for carrying our invention into effect, this is capable of variation and modification without departing from the spirit of the invention. We, therefore, do not wish to be limited to the precise details of the method set forth, but desire to avail ourselves of such variations and modifications as come within the scope of the appended claims.

Having thus described our invention, what we claim as new and desire to protect by Letters Patent is:

1. The method of wrapping individual confections into package of the same and spacing them therein from each other, which comprises arranging a strip of flexible material over movable spacers, laying a number of confections over said strip and pressing them with said strip between said spacers, disposing a wrapper over said confections so as to leave one side of the package thus partially formed unwrapped, removing the spacers, and then folding the wrapper over said unwrapped side to complete the package.

80

2. The method of wrapping individual confections into a package of the same and spacing them therein from each other, which comprises arranging a strip of flexible material over movable spacers, laying a number of confections over said strip and pressing them with said strip between said spacers, disposing a wrapper over said confections so as to leave one side of the package thus partially formed unwrapped, removing the spacers, laying a package stiffener strip over said confections and first-named strip, and then folding the wrapper over said unwrapped side, and over said strips.

85

90

95

3. The method of wrapping articles into a package, which comprises spacing a number of articles from each other in a row by means of a continuous strip of flexible material, arranging a wrapper about said row of articles and strip so as to leave one side of the package thus partially formed unwrapped, arranging a package-stiffening member over said row of articles on said unwrapped side of said package, and then folding said wrapper over said stiffening member and over said unwrapped side to complete said package.

4. The method of wrapping articles into a package and spacing them therein from each other, which comprises arranging a row of articles on a continuous strip of flexible material, inserting portions of said strip between the articles to space the same from each other, arranging a wrapper about said row of articles and strip so as to leave one side of the package thus partially formed unwrapped, arranging a package-stiffening member over said row of articles on said unwrapped side, and finally folding said wrapper over said stiffening member and unwrapped side to complete said package.
